UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

METAL GRAIN DOOR.

Application filed January 3, 1922. Serial No. 526,602.

To all whom it may concern:

Be it known that I, GARTH G. GILPIN, a citizen of the United States, residing at Riverside, in the county of Cook and State 5 of Illinois, have invented new and useful Improvements in Metal Grain Doors, of which the following is a specification.

This invention relates to improvements in side doors for freight cars and more particularly to a metal grain door.

It is an object of this invention to provide a side door that is mounted and operated similar to the usual freight car side door, yet which will, when closed and locked, be 15 grain tight so that the car when not carrying grain may be used for other lading and will need no conversion for grain carrying.

While not necessary to its invention it is preferable to construct this improved door 20 of light weight metal plates strengthened by corrugations or pressed ribs.

While the preferred form of this invention is illustrated upon the accompanying sheets of drawings, yet it is to be understood 25 that minor detail changes may be made without departing from the scope thereof.

In the drawings:

Fig. 1 illustrates in side elevation a portion 30 of the side of a freight car showing this improved side door in closed and locked position.

Fig. 2 is a view in section taken on the line 2—2 of Fig. 1.

Fig. 3 is a view in section taken on line 35 3—3 of Fig. 1, illustrating the grain opening and hinged covering plate in open position.

Fig. 4 is a view in side elevation of a portion 40 of Fig. 3.

Fig. 5 is an enlarged detail view of an upper corner of this door in closed and locked position.

Fig. 6 is a view in section taken on the line 6—6 of Fig. 5.

Fig. 7 is a view in section taken on the line 7—7 of Fig. 1, enlarged and illustrating the lower locking means.

Fig. 8 is an enlarged view in section taken 50 on the line 8—8 of Fig. 1 illustrating the supporting rollers.

To make the door in closed position grain tight it is proposed to provide a half round beading about the exterior of the bottom and sides of the door frame, provide the

door with a corresponding depression adapted to receive the beading when closed, which necessitates that the door be mounted for reciprocation in the closed position, and means for holding the door against the car side with its depressions about the beading.

In carrying out this invention the door 1 is preferably of metal, as shown, made in two or more sections which make it practical to use thin metal reinforced by corrugations and facilitates the forming of the depressions 2 about its sides for receiving the frame beading. The beading 3 is preferably formed by securing metal plates 4 to the inner portions of the sides and bottom of the door frame which plates are extended exteriorly thereof and then bent in a half round away from the opening, as illustrated, which construction not only provides the beading 3 but also reinforces the edges of the door opening. To cause the beading to be continuous the plate 5 on the bottom is bent upward semicircularly at the corners with its beading joined to the side frame beadings.

The door may be supported in any desired manner and in this form is illustrated as supported upon a plurality of door supporting rollers, 6 mounted in roller brackets, 7 secured to the exterior of the car side below the door opening. About each side and continuing across the bottom the body of the door is provided with a pressed out rib forming a depression 2 on the inner side of the door which in the closed position of the door will lay over and when moved towards the car side will receive and engage the door frame beading 3. To allow of the reciprocation of the door to and from the car side, the door is provided with an outstanding door supporting flange 8 at the bottom which travels over the rollers. The rollers and brackets are of the usual construction except that the door rollers have longer shanks than usual which position them further from the car side and a sufficient distance to allow the door to be pulled outward over them to clear the door frame beading.

It is preferable to construct the door supporting flanges 8 of angle iron with one flange depending and secured to the door body, which also will act as a stop to prevent the door being pulled outward entirely over the rollers. The top of the door is preferably provided with a channel 9 interlock-

2
ing with a channel 10 secured to the car side above the door opening to act as a guide and also protect the door from the weather and is of a usual construction, one flange of the 5 channel of the car side being extended upward at right angles and secured to the car and one flange of the door channel being extended downward at right angles for a purpose later to be described and secured 10 along the web of the channel to the body of the door. The other flanges of the respective channels interlock and this construction departs from the usual form of this type in that both channels are deeper to 15 allow of the reciprocation of the door for the purpose described.

From this construction it is seen that while the door may be freely moved to open and closed positions in the usual manner 20 with but little departure from the usual supporting means, it may in closed position be rendered grain tight by moving the door body towards the car side. In order to accomplish this movement mechanically and secure the door in grain tight position it is preferable to provide two series of locks comprising a pair of spaced apart bolts 11 at the top and a pair of spaced apart bolts 12 at the bottom preferably 25 mounted to reciprocate on the outer surface of the door with the outer end of each bolt cut at an angle and adapted to be received within a socket, the contacting of the angular surfaces of the bolt with 30 the sockets wedging the door against the car side. As shown, the bottom bolts pass through guides in the door supporting flange 8 to engage sockets 13 in brackets secured to the car side below the door in a 35 manner similar to the door roller brackets. The upper bolts pass through guides secured to the door body below the door interlocking channel to engage sockets 14 formed by a bracket depending below and 40 secured to the web of the car side interlocking channel. It is preferable to operate the corresponding bolts of each pair in unison and to this end operating levers 45 are pivoted intermediate their length on 50 the outer sides of the car body with the one end of the lever pivotally connected to the end of one bolt and the other end of the other bolt pivotally connected to the lever an equal distance on the other side 55 of the lever pivot so that by up and down movement of the free end of the lever the bolts will be reciprocated at the same time to secure or release the door from grain tight position. To add to the rigidity of 60 the door body the sides are provided with angle irons 16 secured thereto with the outstanding flange in line with the edge of the door and to form protection against sparks and the weather similar angle irons 65 17 are secured to the car side on each side

of the door frame so that when the door is closed and pressed against the car side the door body will be received between the car body angle irons and any space between the door edge and car side will be covered. 70

To provide means for loading and unloading grain the upper panel of the door is in the form of a hinged plate 18 having an integral inwardly extending flange 19 about the bottom and sides. This plate is preferably of light metal having reinforcing corrugations, extends upward behind the depending flange of the door channel and hinged thereto, as shown. The portions 75 20 between the ends of the hinged plate on each side are secured to the back of the web of the door channel and to the panel below and afford space for the passage of the top bolts thereover. The opening 80 closed by the hinged plate is provided with an outstanding flange 21, preferably in the form of an angle iron, about its sides and bottom which is received within the flanged edges of the plate. To hold the hinged plate in different open positions a rod 22 85 is hinged to the upper part of the plate having the lower free end adapted to be engaged in one of a series of stops 23 secured on the side flange of the opening. A bolt 24 adapted to slide through a guide on 90 the door body near the opening is provided to enter a socket 25 on the outer side of the plate to hold it in closed position. This bolt preferably extends downward towards the bottom of the door and is adapted 95 to form a lock for the other bolts by having secured thereto a semi-circular stop 26 above the ends of the operating lever handles 15 with the bolt passing between them so that the stop prevents upward movement of the handles and the bolt passing through a guide under the handles secured to the door. The lower end of the bolt is bent at right angles and in the locked position the bent end 27 will lie parallel 100 to the door and is adapted to pass between the lugs of a car seal 28 so that neither the hinged plate nor the door can be unlocked without breaking the seal. When 105 the seal is removed the bent handle may be rotated out of the seal lugs and then may be pulled down to release the hinged plate, the semi-circular stop being a sufficient distance above the lever handles to allow this limited movement but from its shape will still overlie the ends of the handles and prevent their operation. To release the 110 door bolts the bolt handle is rotated through 180° from its sealed position which moves the semi-circular stop from over the plane of the lever handles allowing their being 115 pushed up to release the door bolts.

By this arrangement the door may be closed and locked in grain tight position 120 and held in locked position but allowing 125 130

the hinged plate to be open for the introduction of the discharge nozzle of a grain chute and after the car has been filled, the hinged plate locked, and then both door and plate 5 locking mechanisms sealed so that neither can be unlocked without breaking the seal.

What I claim is:

1. In a freight car having a side door opening and a side door supported to close and uncover said opening, a beading about the exterior of the door opening and a corresponding recess upon the inner side of the door adapted to receive and engage the beading to form a grain tight closure, said door 10 support allowing reciprocation of the door transversely of the car, and means for holding the door in closed grain tight position, comprising sockets secured to the car sides and bolts mounted upon the door adapted 15 to be operated to engage the sockets and wedge the door against the car side.
2. In a freight car having a side door

opening, a metal side door therefor, a metal beading about the exterior of the door opening, a depression corresponding thereto 25 pressed in the inner side of the door, door rollers mounted on the car side below the door opening, a guide and door cover mounted on the car side above the door opening, a supporting flange upon the bottom of the door adapted to move longitudinally and transversely over the door rollers, a guide member at the top of the door adapted to move longitudinally and transversely with the guide and door cover, 30 the transverse movement of the door allowing inclosed position to engage or free the door recesses and beading; bolt sockets secured to the car side above and below the door opening, bolts on the door when closed 35 adapted to engage in the sockets to wedge the door into grain tight position.

GARTH G. GILPIN
